UNITED STATES PATENT OFFICE.

OSKAR EDM. PEISELER, OF REMSCHEID, GERMANY.

DEVICE FOR SHARPENING SAWS.

SPECIFICATION forming part of Letters Patent No. 702,150, dated June 10, 1902.

Application filed July 20, 1901. Serial No. 69,163. (No model.)

To all whom it may concern:

Be it known that I, OSKAR EDMUND PEISELER, a subject of the Emperor of Germany, residing at Alte Freiheitstrasse 5, in the city 5 of Remscheid, Empire of Germany, have invented a new and useful Improvement in Means for Sharpening Saws, of which the following is a full, clear, and exact specification.

This invention relates to means for sharpening saw-teeth of any kind of saws by hand; 10 and it consists in a saw-file without point and tongue, which is turnably secured in a holder, so that any side pressure upon the holder will not injure the file itself and all 15 the teeth keep their shape.

On the accompanying drawings, Figure 1 is a view of the implement. Figs. 2, 3, and 4 are cross-sections.

The instrument consists of a saw-file *a* and 20 a holder *b*. The first one has neither a point nor a tongue, but is cut off at both ends, so as to form a file of equal section throughout its length. The upper and lower faces of the three-edged file are provided with three center punches *c*, arranged as near as possible to 25 the edge of the file. The holder *b* consists of a bow, in the square ends of which two pointed screws *d* are fixed for the purpose of journaling the file in such a manner that it can freely

move with the edge downward. To prevent 30 its rotation, a projection *h* is provided on the inner face of the strap.

As seen from the sectional figures, the file if inserted into the tooth will equally attack the edges of the same. Side pressures will 35 cause only the holder to assume a side movement. The work with such a file may be done by unpracticed laborers, and the files are considerably cheaper, as the point and tongue are lacking. The movement of the 40 file may be also prevented by a set-screw *g*, projecting through the strap and pressing on the file, as shown.

What I claim, and desire to secure by Letters Patent, is—

A saw-sharpening device consisting of a holder said holder having two oppositely-arranged pointed screws and a projection arranged at its inner side a file adapted to fit between the screws said file being angular 50 and of uniform cross-section, and provided at its ends near each corner with an indentation whereby the file is held eccentrically in its holder for the purpose described.

OSK. EDM. PEISELER.
